UNITED STATES PATENT OFFICE

2,563,246

SLIDER FOR SLIDE FASTENERS

Horace Keech and Noel J. Poux, Meadville, Pa.,
assignors to Talon, Inc., a corporation of Pennsylvania

Application March 16, 1945, Serial No. 583,042

4 Claims. (Cl. 24—205.14)

1

This invention relates to slide fasteners and, particularly, lock sliders of the type disclosed in the Norton et al. patent No. 1,966,457, issued July 17, 1934, and to an improved method of making the same.

In the above mentioned patent, there is disclosed an automatic lock slider including a channeled slider body having a longitudinal lug arranged on one of the wings thereof. There is pivotally attached to the lug at one end thereof, a locking member in the form of a hollow metal member having top, side and end walls. The free end of the locking member is provided with a projection or locking prong which projects in one position into the channel of the slider body into engagement with the fastener elements to lock the slider against movement. A spring or other resilient means is provided for maintaining the locking member normally in its locked position. There is attached to the locking cap member a pull member for manipulating the slider and locking member in a manner well known to those skilled in the art.

The pull member by which the slider is operated consists of a metal tab bifurcated at its inner end with a pair of inwardly oppositely extending finger-like portions or trunnions. The projections or trunnions extend under the side walls of the locking cap member and are freely movable for a substantial distance longitudinally of the slider, the trunnions being confined between the slider body and the inner edges of the side walls of the locking member with the lug forming a separating wall between the trunnions which are disposed at opposite sides thereof.

In order that there be freedom of movement of the pull member with respect to the slider, it is necessary that the distance between the ends of these projections or trunnions be slightly greater than the thickness of the lug, which they embrace. As a result oftentimes, when in use, the pull tab is twisted relative to the slider, thereby frequently causing the trunnions to spread apart to such an extent that the pull member becomes disengaged or displaced from the slider with consequent loss of the pull member, thereby making the slider inoperative.

In order to overcome this difficulty, it has been suggested to provide a transverse aperture through the lug and to attach thereto a pull member having one solid pivotal or trunnion portion which is disposed in the transverse aperture so as to provide a so-called "through and through" pull, thereby eliminating any danger of the trunnion portion becoming disengaged

from the slider body. While this is the most desirable construction for such a slider, heretofore, it was practically impossible to conveniently and inexpensively apply a conventional type pull member to the slider lug and, at the same time, provide a construction possessing the above mentioned requisite. While the pull member could be held on the slider body merely by the locking cap member without the aid of the lug, this is unsatisfactory for the reason that when an excessive pulling force is applied to the pull member to manipulate the slider, the locking member is frequently distorted and displaced from the slider body. It is, therefore, to an improved automatic lock slider having a "through and through" pull and to a method of assembling the pull member in the transverse aperture of the lug of the slider body, that the present invention relates.

20 Accordingly, it is the general object of the present invention to provide an improved automatic lock slider for slide fasteners wherein the pull member is of such construction and is connected to the slider in such a manner as effectively to prevent accidental detachment therefrom, thereby eliminating the above mentioned difficulties.

It is another object of this invention to provide an improved automatic lock slider wherein the pull member is securely attached to the slider, but is attached in such a manner that it will effectively operate the locking member to move the same to its unlocked position when desired.

It is a more specific object of the present invention to provide an improved automatic lock slider wherein the pull member has one solid trunnion or pivotal portion which is disposed movably in an elongated transverse aperture in the lug of the slider with the pivotal or trunnion portion cooperating with the inner wall of said aperture to limit at all times the outward movement of the pull member when a pulling force is exerted thereon when in use, and, at the same time, permitting the locking member to function normally.

45 It is a further object of this invention to provide such a slider wherein by reason of the nature of the pull member and its connection to the slider, danger of disengagement of the trunnion portion of the pull member from the slider and displacement of both the pull member and locking member from the slider, is eliminated, while, at the same time, all the normal functions and advantages of the type of automatic lock slider disclosed in the aforementioned Norton et al. 50 patent, are retained.

Various other objects and advantages of this invention will be more apparent in the course of the following specification, and will be particularly pointed out in the appended claims.

In the accompanying drawings, there is shown for the purpose of illustration, an embodiment and a modification thereof which our invention may assume in practice.

In these drawings:

Fig. 1 is a plan view of a slide fastener having the improved lock slider of our invention incorporated therewith;

Fig. 2 is a perspective view showing the first step in assembling the pull on the slider in accordance with the preferred embodiment of our invention;

Fig. 3 is a plan view of the slider showing the pull assembled thereon;

Fig. 4 is a plan view of the slider showing both the locking cap member and the pull assembled thereon;

Fig. 5 is a side view of the slider assembly, as shown in Fig. 4;

Fig. 6 is a plan view of the slider showing a modified construction of the present invention;

Fig. 7 is a side view of Fig. 6, showing how the pull member is retained in the lug of the slider; and

Fig. 8 is a perspective view of the inner end of the pull member of the modification showing how the trunnion portion is formed.

Referring more particularly to the drawings, there is shown in Fig. 1, a conventional type slide fastener comprising a pair of tapes or stringers 2 having a series of opposed spaced interlocking elements 3 arranged along the beaded edges thereof. There is arranged on the fastener elements, a slider, generally designated 4, for longitudinal movement in either direction therealong to open and close the fastener in a well-known manner.

The slider is generally of the construction as shown in the aforementioned Norton et al. patent, and consists of a hollow body member having spaced upper and lower wing portions 5 and 6, respectively, which are interconnected at one end thereof by means of a neck portion 7 and having inwardly extending flange portions 8 at each side thereof so as to provide substantially a Y-shaped channel in the slider body, through which the fastener elements pass during the opening and closing movement of the slider.

On the outer surface of the upper wing portion 5, centrally thereof, there is arranged integral therewith, a longitudinally extending lug or loop 9 on which there is mounted, a locking arm or cap member 10. The cap member consists preferably of a hollow sheet metal member having top and side walls 10a and 10b, respectively, and preferably end walls, so as substantially to enclose the lug 9, and is pivotally attached thereto, as at 12, adjacent the end of the lug at the upper end of the slider body, preferably by opposed projections carried by the side walls of the cap member which extend into indentations in the opposed sides of the lug 9. The side walls of the cap member are relieved or cut away as at 13 on either side of the lug so that the bottom of each of the side walls is spaced from the upper surface of the wing portion 5 for the purpose of attaching a pull member thereto in a manner hereinafter to be described.

Between the locking cap member 10 and the upper surface of the wing 5, there is arranged in any suitable manner, a resilient member, prefer-

ably in the form of an arcuated leaf or coil spring 14 which is arranged so as to extend or be disposed to the rear side of the pivotal connection 12 and bears against the inner side of the cap member.

On the opposite end of the cap member there is arranged a locking prong or projection 15, which is formed preferably as an extension of the side wall and which projects normally through an opening 16 in the top wing of the slider into the Y-shaped channel into engagement with the fastener elements 3 to lock the fastener in a well-known manner. It will be seen that the spring 14 tends to urge the locking cap member 10 about its pivotal connection with the lug so as to project normally the locking projection 15 between any pair of fastener elements.

The pull member or tab 17 may be of any convenient form and consists preferably of a flat metallic member having a large rectangular shaped opening 18 at its inner end so as to provide a pair of spaced apart leg portions 19 terminating in a solid pivotal or trunnion portion 20 at its extreme inner end by means of which the pull is pivotally attached to the slider in a manner hereinafter to be described. This trunnion or pivotal portion is disposed loosely in an elongated transversely extending aperture 21 in the lug 9, with the trunnion portion extending to either side of the lug so as to be disposed in the relieved or cutaway portions 13 of the locking cap member 10 positioned on either side of the lug. When the pull member is manipulated to operate the slider, the trunnion or pivotal portion 20 bears against the bottom edges of the side walls of the locking cap member, thereby moving it about its pivotal connection, at 12 against the action of the spring 14, thereby withdrawing the locking prong 15 from the channel of the slider and out of engagement with the fastener elements 30 therein in a well-known manner.

According to the present invention there is arranged in the upper wall of the lug 9, substantially centrally thereof, a transverse slot 22 which communicates with the transverse aperture 21 in the lug. As shown in Figs. 2 and 3 of the drawings, this transverse slot is positioned angularly of the lug 9 and preferably at the smallest angle possible with the longitudinal axis thereof for reasons which will become apparent hereinafter. The width of this angular transverse slot 22 is just slightly greater than the thickness of the inner end of the pull member 17 and this transverse slot is provided for the purpose of attaching the pull member 17 to the lug in a manner now to be described.

In assembling the pull member 17 on the slider, the pull member is positioned substantially perpendicular to the plane of the upper surface of the top wing, as shown in the full lines of Fig. 2 of the drawings, with the trunnion portion 20 disposed directly opposite the transverse slot 22 in the lug 9 and in alignment therewith. The trunnion or pivotal portion of the pull member is then inserted in the transverse slot 22 and moved therethrough until it is disposed in the transverse aperture 21 of the lug, as shown in the broken lines of Fig. 2. The pull is then twisted slightly so that the trunnion portion is disclosed substantially perpendicular to the lug with the leg portions 19 disposed substantially parallel thereto to either side thereof, as shown in Fig. 3. In such position, it will be seen that the trunnion portion 20 is prevented from passing back through the transverse slot 22 due to

the angular position thereof relative to the trunnion portion.

After the pull member has been positioned on the lug in the manner as above described, the locking cap member 10 is mounted thereon in the conventional manner so as to be pivotally attached thereto, as at 12, to provide a complete slider assembly, as shown in Figs. 4 and 5 of the drawings. It will be seen that the opening 18 between the leg portions 19 of the pull member, is substantially filled after assembly of the locking cap member, thereby preventing any appreciable twisting movement of the pull member relative to the lug and slider body. Since the trunnion portion of the pull member is prevented from twisting by the locking member, consequently the trunnion portion will be prevented from becoming aligned with the angular transverse slot 22 in the lug, thereby eliminating any danger of the trunnion portion passing back therethrough.

As hereinbefore described, it will be seen, as shown in Fig. 5 of the drawings, that the trunnion portion 20 of the pull member will cooperate with the bottom edges of the side walls of the locking cap member 10 to move it about its pivotal connection at 12 with the lug to unlock the slider when a pulling force is exerted on the pull member. The outward movement of the pull member as a result of such pulling force, will be limited due to the cooperation of the trunnion portion of the pull with the upper wall of the transverse aperture 21. In such a slider it is well-known that it is desirable that the pull member be movable longitudinally of the slider in order to avoid the pulling force from being centered substantially at the center of the slider body. For this reason, the transverse aperture 21 is elongated so as to permit the trunnion or pivotal portion 20 of the pull member to travel an appreciable distance from one end of the slider to the other. In such longitudinal movement of the trunnion portion, it is desirable that it have a continuous bearing surface throughout its travel along the upper wall of the transverse aperture 21 in the lug. In the present construction, while the lug 9 is slotted at 21 to break the continuous surface of this upper wall, a continuous bearing surface is provided by disposing the slot 22 angularly relative to the lug and this is one of the most important aspects of the invention. In other words, the trunnion portion 20 will contact the upper wall of the transverse aperture continuously throughout its longitudinal travel relative to the slider, thereby eliminating any danger of the trunnion portion passing through the slot 22 and thereby preventing the locking cap member from being subjected to any excessive pulling force which might tend to distort or displace the locking cap member from the lug.

In Figs. 6, 7 and 8 of the drawings, there is shown a slight modification of the slider of our invention. In this construction, there is provided a lug 9a, substantially centrally thereof, a transverse slot 23, which extends substantially at right angles to the lug and communicates with a transverse aperture 21a therein. As shown in Fig. 8, the trunnion 20a of the pull member 17a is dimpled or offset as at 24 substantially at the center thereof, so that this central portion is disposed out of the plane of the remainder of the pull, for a purpose to be described.

In assembling this modified form of slider, the pull member is positioned as before substantially perpendicular to the upper wing of the slider to

one side of the lug with the leg portions 19a adjacent the lug disposed next thereto directly opposite and in alignment with the transverse slot 23 therein, as shown in the broken lines of Fig.

5 6 of the drawings. The pull member is then moved laterally relative to the slider body and lug 9a with the adjacent leg portion 19a inserted in and moved through the transverse slot 23 of the lug, until the trunnion portion 20a is disposed in the transverse aperture 21a, as shown in the full lines of Fig. 6. The pull member is then moved downwardly so as to lie flat against the slider, as shown in Fig. 6. The locking cap member 10a is then assembled thereon in the same manner as hereinbefore described. After the cap member is assembled on the lug, it will be seen that any appreciable lateral movement of the pull member relative to the slider and lug, is arrested, thereby preventing either leg portion 19a from passing back through the transverse slot 23. In this construction as in the preferred construction, it will be understood that the width of the transverse slot 23 is slightly greater than the thickness of the inner end of the pull member but that the dimpled or offset portion 24 in the trunnion presents an over-all thickness greater than the width of the slot 23, thereby preventing the pivotal portion from passing therethrough. Likewise, in this embodiment, there is provided a continuous bearing surface for the trunnion on the upper wall of the transverse aperture 21a throughout its travel relative thereto, thereby eliminating any danger of the trunnion portion from subjecting the cap member to any excessive pulling force. In other words, any excessive pulling force to which the pull member is subjected will be absorbed by the lug 9a and not by the locking cap member 10a.

As a result of our invention, it will be seen that 40 with a slider constructed in such a manner the operation of connecting or attaching the pull member or tab to the lug of the slider is accomplished in an extremely simple and effective manner, and at the same time, a strong and rugged connection is provided for the pull member. If 45 the slider body be die-cast it will be seen that both the transverse slots 22 and 23 together with the aperture 21 in the lug can be conveniently formed during the die casting operation.

50 While we have shown and described one embodiment and a modification thereof which our invention may assume in practice, it will be understood that this embodiment and modification are merely for the purpose of illustration and description, and that various other forms may be devised within the scope of our invention as defined in the appended claims.

What we claim as our invention is:

1. In a slider for slide fasteners of the class 60 described, a body member having upper and lower spaced apart wings so as to provide a channel therebetween through which fastener elements are adapted to pass for engaging and disengaging the same, a longitudinally extending lug arranged on the outer side of one of said wings, said lug having a transverse aperture arranged therethrough intermediate the length thereof, and a pull member having the pivotal portion thereof disposed in said aperture, the outer wall of said lug having a slot arranged angularly and transversely thereof communicating with said aperture through which the pull member is adapted to be inserted to position the pivotal portion thereof in said aperture when being assembled on said lug, said slot being constructed

and arranged so as to prevent the pivotal portion of said pull member from passing normally back through said slot after it has been assembled in the transverse aperture of said lug and so as to provide substantially a continuous bearing surface for the pivotal portion of said pull member along the inner side of the outer wall of said lug against which surface the pivotal portion of said pull member is adapted to bear in its longitudinal movement from one end of the lug to the other.

2. In a slider for slide fasteners of the class described, a body member having upper and lower spaced apart wings so as to provide a channel therebetween through which fastener elements are adapted to pass for engaging and disengaging the same, a longitudinally extending lug arranged on the outer side of one of said wings, said lug having a transverse aperture arranged therethrough intermediate the length thereof, a pull member having the pivotal portion thereof disposed in said aperture, the outer wall of said lug having a slot arranged angularly and transversely thereof communicating with said aperture through which the pull member is adapted to be inserted to position the pivotal portion thereof in said aperture when being assembled on said lug, and a locking member pivotally attached to said lug and bridging the angular transverse slot therein, said locking member adapted to prevent the pivotal portion of said pull member from passing normally back through said slot after it has been assembled in the aperture of said lug, said slot constructed and arranged so as to provide substantially a continuous bearing surface along the inner side of the outer wall of said lug against which surface the pivotal portion of said pull member is adapted to bear in its longitudinal movement from one end of the lug to the other.

3. In a slider for slide fasteners, a slider body having a fastener element guide channel therein, a longitudinal lug projecting from one side of said slider body having an elongated transverse aperture arranged therethrough, a locking member pivotally connected to said lug at one end and superimposed thereon, said locking member having thereon a projection adjacent its free end projectable into said channel for locking said slider and retractable therefrom for unlocking the same, resilient means for constantly urging the free end of said locking member toward said slider body to maintain said projection in said channel to lock the slider, and a pull member terminating in a trunnion portion which is disposed in the transverse aperture of said lug, said trunnion portion in one position of said pull member adapted to engage said locking member for lifting the free end portion thereof against the force of said resilient means to unlock said slider, said lug having a transverse slot arranged angularly in the outer wall thereof having a width slightly greater than the thickness of said pull member and through which said pull is adapted to be inserted to position the trunnion portion thereof in said aperture, both said slot and said trunnion portion being constructed and arranged so as to prevent said trunnion portion from pass-

ing through said slot after the locking member has been assembled on said lug and so as to provide substantially a continuous bearing surface along the inner side of the outer wall of said lug against which surface the trunnion portion of said pull member is adapted to bear in its longitudinal movement from one end of the lug to the other.

4. In a slider for slide fasteners, a slider body having a fastener element guide channel therein, a longitudinal lug projecting from one side of said slider body having an elongated transverse aperture arranged therethrough, a hollow locking member having top and side walls extending over the top and sides of said lug and pivotally connected to said lug at one end, said locking member having thereon a projection adjacent its free end projectable into said channel for locking said slider and retractable therefrom for unlocking the same, resilient means for constantly urging the free end of said locking member toward said slider body to maintain said projection in said channel to lock the slider, and a pull member terminating at one end in a trunnion portion which is disposed in the transverse aperture of said lug, said trunnion portion in one position of said pull member adapted to engage the edges of the side walls of said hollow locking member for lifting the free end portion thereof against the force of said resilient means to unlock said slider, said lug having a transverse slot arranged angularly in the outer wall thereof having a width slightly greater than the thickness of the pull member and through which said pull member is adapted to be inserted to position the trunnion portion thereof in said aperture when being assembled on said lug, both said slot and said trunnion portion being constructed and arranged so as to prevent the trunnion portion of said pull from passing normally through said slot after the locking member has been assembled on said lug and so as to provide substantially a continuous bearing surface along the inner side of the outer wall of said lug against which surface the trunnion portion of said pull member is adapted to bear in its longitudinal movement from one end of the lug to the other.
